UNITED STATES PATENT OFFICE

ALOIS ELSNER, OF BRUNN, CZECHOSLOVAKIA

NONSLIP DEVICE FOR USE WITH SKIS

Application filed March 19, 1930, Serial No. 437,118, and in Czechoslovakia January 23, 1929.

Ascending on skis in hilly or mountainous places is extremely hard. The ski is apt to slip back, so that the skier will soon get tired.

It also frequently happens that a novice at skiing, when descending, or traveling downhill across a forest, or on stony ground, will lose the command of his skis, and rush into obstacles, whereby serious accidents may occur.

10 The object of the present invention is to overcome these drawbacks, by increasing the friction of skis. Arrangements in which strips of sealskin or the like are fastened to the bottom faces of the wooden runners are known. Such skins, however are expensive, and liable to wear away when getting wet and, subsequently, freezing in. Moreover, these sealskin strips are either pasted on or otherwise secured to the skis by some complicated device by which an eventually present anti-friction wax layer will be injured.

The device according to the invention comprises a very great number of metal teeth fastened to the bottom of the skis. These 25 metal teeth or barbs are similar to the cards used in textile works, and, like them, are best stuck through a strip of leather or the like, which is fastened to the ski by means of straps, or lace. The wire used for the manu- 30 facture of these teeth or barbs has, preferably, a triangular cross section, and the teeth are fastened to the skis in a manner which, when the skier is progressing, will permit one one edge of the triangle to cut the snow, 35 while the opposite side will oppose considerable resistance to slipping downhill.

In the drawing, an embodiment of the invention is shown by way of example. Figure 1 is a view of the non-slip device seen from below, Figure 2 is a section on the line I—I of Fig. 1. Figure 3 shows a cross section of the wire used for the manufacture of said teeth, on an enlarged scale, the direction of the course being indicated by an arrow. Numerous wire teeth 2 are run, in rows, through a strip of leather or the like 1. The simplest way to effect this is similar to the manner in which this is accomplished in cards, namely, to bend bits of wire to U-form and stick said wires through the strip 1. The ends of the

bits of wire are bevelled, and the teeth are run in such a manner that the angle contained between them and the direction of the course indicated by the arrow A is an obtuse angle α . To protect said leather strip from wear, a metal sheet may be applied to the bottom face of said strip, from which sheet the teeth will project.

The fastening of the strip 1 to a ski may be effected by pasting to the back of the strip a support 3 of waterproof fabric, to which support straps 4 and 5 are attached. To the ends of the straps 4, buckles are secured, by which straps 4 and 5 can be connected to each other. By means of said straps the non-slip device is buckled to a ski 6. The length of the non-slip device is about 20 cm., and the device is attached in front of the strapping. This will allow the non-slip device to be attached, or removed, in a few moments. Said 70 non-slip device is therefore particularly adapted for short excursions, say, in training fields or for travelling on hilly ground. Owing to its small size, a pair of such non-slip devices, after removal, may be tucked into a rucksack, or pocket of a coat, or fastened to the belt, so as to be always ready for use. Said device does not injure an eventually present non-friction wax layer.

What I claim is:

1. A non-slip device for use with skis comprising metal teeth adapted to be fastened to the bottom of said skis, said teeth having a triangular cross section.

2. A non-slip device for use with skis comprising a support of water-proof fabric, a strip of leather secured thereto and metal teeth secured to said strip of leather.

3. A non-slip device for use with skis comprising a support of water-proof fabric, a strip of leather secured to said support, metal teeth secured to said strip of leather and means attached to said support for securing said device to a ski.

4. A non-slip device for use with skis comprising a support of water-proof fabric, a strip of leather secured to said support, metal teeth secured to said strip of leather and straps attached to said support.

5. A non-slip device for use with skis com-

prising a strip of leather, metal teeth secured to said strip of leather and the free ends of said teeth being inclined with respect to the surface of said strip of leather.

5 6. A non-slip device for use with skis comprising a support, a strip of leather secured to said support, metal teeth secured to said strip of leather, straps attached to said support and buckles secured to said straps where-
10 by said straps may be connected to one another for securing said device to said skis.

In testimony whereof I have signed my name to this specification.

ALOIS ELSNER.
